UNITED STATES PATENT OFFICE.

JOHN W. CHISHOLM, OF WARDLOW, ALBERTA, CANADA.

IN INKSTAND.

Application filed December 3, 1922. Serial No. 384,826

To all whom it may concern:

Be it known that I, JOHN W. CHISHOLM, a subject of the King of Great Britain, residing at Wardlow, in the Province of Alberta and Dominion of Canada, have invented certain new and useful Improvements in Inkstands, of which the following is a specification.

This invention relates to an improved ink dispensing arrangement.

The primary object of this invention is the provision of a novel ink container which embodies details whereby ink may be dispensed in facile manner for use.

An important object of this invention is the provision of an improved closure and valve arrangement for ink receptacles and wells.

Other objects and advantages of this invention will be apparent during the course of the following detailed description.

In the accompanying drawing, forming a part of this specification, and wherein similar reference characters designate corresponding parts throughout the several views,

Figure 1 is a transverse cross sectional view showing the improved ink well, taken substantially on the line 1—1 of Figure 2.

Fig. 2 is a vertical cross sectional view, taken through the improved ink stand, showing the details thereof in position for dispensing a supply of ink.

Fig. 3 is a fragmentary cross sectional view, showing the improved closure arrangement as used in connection therewith.

In the drawing, wherein for the purpose of illustration is shown but the preferred embodiment of this invention, the letter A generically indicates the improved ink stand, which more specifically embodies the bottle or receptacle B, closure and valve arrangements C, and base or well member D.

The receptacle B may be the ordinary ink bottle which includes the body portion 10 providing a chamber 11 in which a quantity of ink or other liquid 12 is adapted to be disposed. A neck 13, preferably externally screw threaded, may be included in the construction of the bottle B, which provides a passageway or opening 14 into which a plug portion 15 of the closure arrangement C is normally seated. An annular shoulder 16 is preferably provided at the base of the opening 14, and at the juncture of the neck

13 with the body 10, and upon which the plug 15 normally seats.

The closure member plug 15 is preferably of cylindrical formation and is provided with a passageway axially therethrough which is formed of the outer and inner tapered openings 18 and 19 respectively, relatively converging from the outer and inner surfaces respectively of the plug member 15, to provide the constricted opening 20 preferably at the center of the passageway formed of the tapered portions 18 and 19. The closure device C also includes a bolt member 25 which is provided with a head 26, an adjacent tapered portion 27, and a screw threaded shank 28. The head 26 extends annularly from the greatest cross dimension of the tapered portion 27, and is adapted for cooperation upon the inside surface of the plug member 15, so that the tapered portion 27 cooperates in the tapered portion 19 of the plug opening; the screw threaded shank 28 being adapted for extension outwardly of the outer surface of the plug 15 and for receiving a nut member 30 in adjustable manner. This nut member 30 includes a tapered or bubbular projecting portion 31 facing the plug 15, and which is adapted for cooperation in the tapered opening portion 18 of plug 15 to provide a seal, whereby the passageway through the plug 15 may be closed when the nut is drawn into tight engagement with the outer surface of the same, so that the tapered portions 27 and 31 are respectively disposed in snug engagement within the tapered portions 19 and 18 of the plug passageway. It is preferred that the nut 30 be provided with an inwardly converging depression 32, which provides a pocket 33 at the extreme convergence of said depression within which the end of the screw threaded shank 28 is overturned or peened, as at 34, to prevent any possibility of accidental detachment of the nut from the bolt 25.

Referring to the base or well member D, the same includes the supporting flange portion 35 from the central portion of which the supporting neck 36 rises, and which is provided with the screw threaded opening 37 adapted to detachably receive the neck 13 of the receptacle or bottle B. This neck portion 36 below the screw threads thereof provides a chamber 38 which has communication as by ports 39 and

40, with oppositely disposed wells 41 and 42 respectively, which are open topped.

As is illustrated in Figure 2 of the drawing, the closure member C may be used as 5 a stopper or cork for the ordinary ink bottle B, and may be sold as a part thereof for accessory use in connection with the stand D. Utilized in connection with the base or well member D, the nut 30 is loosened or adjusted upon the screw threaded 10 stem 28 so that the bolt member 25 and nut 30 may cooperate to provide a valve for the tapered portions 18 and 19 of the plug passageway.

15 In operation, the nut 30 having been loosened upon the bolt 25, upon inverting of the bottle B and screw threading the same into the neck of the base member D, the 20 conical projection 45 which extends upwardly from the bottom of the well D, will seat within the converging depression 32 of the nut 30, so that the tapered portion 27 of bolt 25 will be unseated from the passageway 19, and when the bottle is entirely 25 seated in the well member D, the passageway through the plug 15 will be sufficiently cleared to permit flow of liquid 12 into the chamber 38 of the well D, from whence the liquid flows into the wells 41 and 42, 30 through the ports 39 and 40. From this arrangement it is obvious that the bolt 25 will be maintained in perfect vertical position, free of contact with the plug 15, by reason of the capable manner in which the 35 nut engages the conical projection 45 against liability of lateral displacement. It is to be noted that there is still space intermediate the peened end 34, and the top surface 34^a of the conical projection 45, whereby the bolt 25 may be adjusted to vary the clearance of the passageway through the plug 15, should there be a restricted or too free flow of ink therethrough.

40 The liquid or ink within the receptacle B, when the valve or closure arrangement C is open, acts on a barometric principle, and the vacuum provided by the liquid 12, when the bottle B is inverted, will support the liquid 12, whereby the same may be 45 properly supplied to the wells 41 and 42 for use, and the ink in said wells will be maintained at a constant level notwithstanding the use of the same.

It is preferred to provide a cover member 50 for the wells 41 and 42, which may 55 be of any shape consistent with the number of well chambers provided. This cover member 50 preferably includes a sleeve portion 51 which may engage the neck 36 for sliding rotation thereon; it being preferred that a shoulder 36^a be provided on the neck 36 upon which the cover 50 rests. Lateral closure extension 52, having upwardly extending hand engaging knob 53, 60 may be provided for the well chambers 41

and 42, substantially as illustrated in Figures 1 and 2 of the drawing.

In order to utilize the improved ink stand, it is merely necessary to oscillate or 5 swivel the cover 50 laterally, substantially 10 into the position illustrated in dotted lines in Figure 1 of the drawing, whereby the well chambers 41 and 42 will be uncovered and a writer is free to utilize the fluid in 15 said wells. Rubber guards may be disposed 20 within the chambers of the wells 41 and 42 for protecting pen points and the like.

Various changes in the shape of this invention, such as provision of one or a plurality of well chambers; size of the various 25 details; and arrangement of parts, such as the omission of the cover member 50, may be made to the form of the invention herein shown and described, without departing 30 from the spirit of the invention or the scope 35 of the claims.

I claim:

1. As an article of manufacture, an ink 40 container including a receptacle, and closure means comprising a plug carried by said receptacle having a passageway therethrough, a bolt member including a head and a screw threaded stem, said head adapted for cooperation upon the inner end of said plug, and a nut adapted for adjustable engagement with the screw threaded stem of said bolt outwardly of the plug member and including a portion adapted for seating on the outer end of said plug member whereby the bolt and nut may serve as a closure for sealing the passageway through said plug. 45

2. As an article of manufacture, an ink 50 container comprising a receptacle of bottle formation including a neck providing an opening therethrough and having an annular seat inwardly thereof, a plug member 55 adapted for seating within the neck of said bottle upon said annular seat and having a passageway therethrough tapering from both outer and inner sides of said plug member to a constricted outlet intermediate the outer and inner surfaces of said plug member, a bolt member including a tapered portion 60 adapted for cooperation upon the inner tapered portion of said plug passageway and including a screw threaded shank adapted for outward extension from said passageway of the plug member, and a nut having a screw threaded opening therethrough adapted for adjustable engagement over the 65 screw threaded shank of said bolt, said nut including a tapered portion facing said shank and adapted for cooperation with the tapered portion of said plug passageway facing said nut. 70

3. As an article of manufacture, an ink 75 container comprising a receptacle having an outlet opening therein, a stem including a valve head for cooperation in said outlet opening, and a sleeve member adjustable on 80

said stem adapted to be adjusted therealong whereby the same may be properly spaced from the valve head so that the same may be moved to permit ink to flow through said outlet opening, said member adapted for adjustment upon said stem so that the valve head and sealing member may be clamped over the outlet opening of said container to prevent flow of ink therefrom.

10 4. A device of the class described comprising a base member including a supporting portion having an upwardly extending neck with a chamber therein, said base member having wells laterally of the neck portion thereof and in communication with the chamber thereof whereby ink may flow into said wells, and a closure device for said ink member including a collar swingable upon said neck portion of the base member with lid extensions thereon for disposition over dip openings in said wells.

15 5. As an article of manufacture, an ink container comprising a receptacle having an outlet opening therein through which ink

may flow, and a pair of relatively movable 25 and adjustable parts carried by said container within the outlet opening thereof adapted to be spaced so that the same may move in said outlet opening to act as a valve to permit a quantity of ink to flow from the 30 container through said outlet opening, said relatively movable parts being so related that they may be clamped in said outlet opening to prevent flow of ink from said container.

3. An ink well comprising a base portion providing an upwardly extending substantially conical projection therein, a container supported by said base portion having an outlet opening therein, and a valve 40 device supported within said outlet opening having a recess therein adapted to rest on said conical portion of the base member whereby the same may be adjusted within the outlet opening of said container to permit flow of ink from the container into said base portion of the ink well.

JOHN W. CHISHOLM.
